UNITED STATES PATENT OFFICE.

JACOB BERMAN, OF REVERE, MASSACHUSETTS.

COLLAPSIBLE PLATFORM SCAFFOLD LADDER.

Application filed May 6, 1925. Serial No. 28,517.

The scaffolding structure involved herein is of the collapsible ladder type carrying a platform. Such a structure affords various features of advantage over fixed scaffolding and over improvised structures in which ladders are employed to support a platform. One of the great difficulties with any such structure which is to be used from time to time and at different places is its portability and compactness, whether in transit from one job to another, or whether in storage between jobs. It is furthermore of great importance that such structure be readily set up and knocked down, and also that it be capable of a wide range of adjustment while still being strong and stable.

My invention involves improvements embodying these features and for the purposes of illustration I have shown an embodiment of my invention having a maximum degree of the advantages sought, with a minimum of complication and expense. Such an embodiment is shown in the accompanying drawings. Throughout the specification and drawings like reference characters are employed to indicate corresponding parts, and in these drawings:

Fig. 1 is a perspective view of such a scaffold ladder in erected and fully extended position.

Fig. 2 a section on the line 2—2, of Fig. 1, looking down the ladder, but with the lower end structure omitted.

Fig. 3 is a fragmentary side view of the extensible ladder portions.

Fig. 4 a detail of a brace portion.

Fig. 5 a side view of the scaffold in its lowest position, and

Fig. 6 a similar view with the scaffold in its intermediate position, the platform railing being omitted in Figs. 5 and 6.

In such a structure I provide a base 1 which affords a stable support on the floor or on the ground or on a wheeled truck (not shown) where such is desired. On the base 1 there are a pair of longitudinal flanges which may be conveniently formed of angle irons 2 bolted to the base plate. On each side of the base and adjacent one end thereof I provide semi-circular bearings 9 and 10, having substantially semi-circular bearing edges on which are cut racks 9¹ and 10¹. These sectors 9 and 10 may be conveniently bolted to the upstanding flanges 5 of the angle irons 2 by bolts as at 3, 4 and 5. Pivoted on a shaft 11 which is mounted cen-

trally of the sectors 9 and 10 are the sides of the lower section of the ladder 22. As will be seen by reference to Fig. 2, these are channel irons with the channels faced inwardly and in them are mounted the rungs 21. Adjacent the lower end of the ladder are a pair of shafts 19 and 20. The upper shaft 20 has a crank 25 by which it may be rotated, and has a pinion 16 at one end meshing with the pinion 15 on a shaft 19, and preferably a pinion 18 meshing with a pinion 17. The pinions 17 and 15 mesh with the semi-circular racks 10¹ and 9¹, respectively, so that the ladder section can be swung at any desired angle or raised or lowered by a swinging movement on 11 as an axis.

Slidably mounted on one flange of the side members 22 is the second extension 23. This member consists of the main channel member 23 and is itself a channel member, the members of the two sides having their channels directed outwardly so as to have bearing on one of the flanges of the lower member 22. The opposite flange of the channel member 23 has a corresponding engagement with the flange of the top member 24. These top members are similar pieces but the top members have their valleys faced inwardly as in the case of the member 22. The members are further guarded and braced by a channel shaped filler 26 which is attached to the bottom members of the side pieces 23 so that the outwardly directed flanges of the combined members 23 and 26 each embrace an in-turned flange of the members 22 and 24. The members 22 carry an extension gear shaft 30 adjacent each end. These shafts are rotated by standard handle members 25¹ and each have a pinion 27. The lower pinion 27 meshes with a rack 28 on the middle section 23. The sections are thus capable of being elevated or lowered independently. Just below the lower shaft 30 is a cross piece 31 carrying a pawl 29 and a corresponding pawl 29 on cross piece 31 is also provided adjacent the upper shaft 30. These pawls are balanced to ratchet on the racks 28 and 28¹ so that the ladder extensions will be firmly held at any degree of elevation to which they may be raised.

At the opposite end of the platform 1 and detachably pivoted to the side flanges 2 are a pair of scaffold posts 38. These are provided with rungs 39 so that the scaffold

may be utilized as a ladder if desired, and so that they may be utilized to support the platform 32 which has underlying members 34 and is preferably provided with a guard rail 35. The scaffold comprises three of these sections 38 corresponding in length to the ladder sections 22, 23 and 24. These sections are pivotally connected as at 38¹, and are preferably provided with slots 38² adapted to engage over studs similar to the studs 37¹ detailed in Fig. 4. The scaffold extensions 38 are cross braced by a series of struts 37 pivoted at one end to one member and having a hook engagement 37¹ at the other. These may be disposed as desired and are arranged to swing out of the way when the sections are collapsed.

The device can be operated as a low scaffold with the platform 32 as shown in Fig. 5 with the ladder sections 24 and 23 run down into substantial coincidence with the section 22. When working at a higher level the section 23 carrying the section 24 may be run up until the platform 32 is at the elevation shown in Fig. 6. The high level is shown in Fig. 1 and intermediate levels may be attained by relative positioning of the ladder sections by turning the cranks 25. As indicated in dotted lines in Fig. 5, the combined sections may be swung on the pivot 11 of the section 22 by simple rotation of its operating crank. When so collapsed the scaffold members 38 can be folded up after unhooking the struts 37. The platform 32 is detachably mounted at the end of the upper section 24 by the removable pintle 33. The scaffold thus dismantled may be conveniently stored or shipped. Where the scaffold is not needed the ladder member may be operated as any extension ladder without the platform, and without the scaffold members. The scaffold members also provide a light, foldable ladder easily handled and adapted for ordinary use as a lad-

der or by bending the end sections at right angles to the center section form a light struss or scaffold independent of the rest of the device.

Various modifications may be made in the detail structure of the ladder and the scaffold and the operating members and all without departing from the spirit of my invention as set forth in the appended claims.

What I therefore claim and desire to secure by Letters Patent is:

1. In a scaffold structure, a base, a ladder member comprising a plurality of extensions, a runged scaffold member comprising a plurality of extensible units, and a platform carried by the ladder member at one end, and supportable by the scaffold member and detachable brace members disposed between the ladder and scaffold member.

2. In a scaffold structure of the class described, a base, an extension ladder hinged thereto, means for angularly swinging the ladder, a foldable scaffold support detachably mounted on said base, a platform carried by the top section of the ladder and having a free end supportable on the scaffold member.

3. In an extension ladder structure, a plurality of sections each including a channelled side member construction, two of said members having the flanges of their channels disposed in the same direction, and an intermediate section having the flanges of its said members disposed in an opposite direction and engaging the inner flanges of the first named section, and a channel filler piece carried by the intermediate section and disposed with its channel in the same direction as its main side member, and externally bearing on the outer face of said included flange members of the first named sections.

JACOB BERMAN.
